CLIO B. YAW, OF ARLINGTON, NEW JERSEY, ASSIGNOR TO REMINGTON TYPEWRITER COMPANY, OF ILION, NEW YORK, A CORPORATION OF NEW YORK.

TYPE-WRITING MACHINE.

1,015,373.

Specification of Letters Patent. Patented Jan. 23, 1912.

Application filed October 26, 1910. Serial No. 589,148.

To all whom it may concern:

Be it known that I, CLIO B. YAW, citizen of the United States, and resident of Arlington, in the county of Hudson and State 5 of New Jersey, have invented certain new and useful Improvements in Type-Writing Machines, of which the following is a specification.

My invention relates to typewriting machines, and it has for its principal object to provide an improved type action for visible typewriters, and especially for front strike typewriters.

One of the principal objects of the invention is to reduce the number of jointed connections between the key levers and type bars and also between the universal bar and the type bars.

My invention also contemplates improving the type action in respect to the readiness with which it can be assembled.

It is also designed to improve the application of the restoring springs.

Another object of the invention is to provide improved means for locking the type bars against rebound, and another is to improve the type action in respect to simplicity and general efficiency.

Other objects will appear in the course of the description.

My invention consists in certain features of construction and combinations and arrangements of parts, all of which will be fully set forth herein and particularly pointed out in the claims.

In the drawings, Figure 1 is a front to rear vertical sectional view of a typewriting machine having my invention embodied therein, only so much of said machine being shown as is needed to understand the invention. Fig. 2 is an enlarged fragmentary side view of the upper end of one of the key levers and its connection with the type bar operating link. Fig. 3 is a front elevation in vertical section, the section being taken for the most part on the line $x-x$ of Fig. 1. Fig. 4 is a fragmentary view in horizontal section on a larger scale than Figs. 1 and 3 and showing the means for regulating the tension of the restoring springs. Fig. 5 is a top plan view, partly in section, of the key lever system, this view being more or less diagrammatic in character.

For the sake of illustration, I have here shown my improved type action mounted in,

or applied to, a machine which in other respects is substantially like the Remington No. 10 typewriter. It will of course be understood that the invention can be applied or adapted to machines differing from the one shown.

In the drawings, 1 indicates the base of the main frame, 2 the corner posts, and 3 the top plate. These parts are like those of the Remington No. 10, except that the forward extension 4 of the base 1 is somewhat modified in order to support properly the stems of the printing keys, as will hereinafter appear. The machine is equipped with a carriage which supports a platen 5. The carriage may be of any suitable construction, such, for example, as is well known in the Remington machine referred to.

The machine includes a series of front strike type bars 6, each pivoted at 7 in a hanger 8, and said hangers are secured by screws 9 to the front face of the type bar segment 10. The free ends of the type bars normally rest on a pad 11 mounted in a segmental support 12 near the front of the machine. The type bar segment 10 and the forward segment 12 are both secured as by screws to two bars 13, one at either side of the machine, the two segments being connected to the rear and forward ends respectively of said bars. In Fig. 3 are shown the screws 14 by which the segment 10 is secured to the bars 13. Said bars are fastened to the under side of the top plate 3 by four screws 15, two for each of said bars. The construction is such that the system of type bars as an entirety can be removed from the machine by removing the screws 15, in which case the two segments 10 and 12, with the type bars mounted therein, can be taken out of the machine in an assembled relation. The type bars here shown, together with their mode of mounting on the segment 10 and also this removable framework in which the type bars are mounted, are all here shown as substantially identical with the corresponding parts of the Remington No. 10 machine, with a single exception that will be pointed out hereinafter.

The type bars are operated by a series of key levers, each of which, as here shown and considered from the point of view of its physical outline, has three arms, namely, an upstanding arm 16, a forwardly directed

arm 17 extending into the keyboard and a rearwardly directed arm 18 extending back to the pivot of the key lever. Considered mathematically, each of these key levers is simply an angled lever pivoted at its rear and lower part to a stationary pivot and having a forwardly directed lever arm that is operated by a key and an upwardly directed lever arm that acts on the type bar. Each of the key levers is pivoted at 20 in a hanger 21 and each of said hangers is, as here shown, secured by two screws 22 to the under side of a stationary frame plate 23. Each of the arms 16 is curved around the forward edge of this frame plate, as shown in Fig. 1, and extends thence upward and at an inclination toward the rear and all of the said arms have their upper ends extending substantially vertically and in approximately the same transverse vertical plane. This last is partly a matter of mechanical convenience to get the upper ends of the levers in an arc, and is partly to enable the key levers to coöperate properly with a comb plate 24 and a universal bar 25. Said comb plate, as here shown, consists of a strip of sheet metal secured by screws 26 to the under side of the segment 12 and having suitable slots cut therein to guide the arms 16. This comb plate is bent into segmental form so that it coöperates with the several key levers near their respective upper ends. Said comb plate appears in front elevation in Fig. 3. The lever arms 16 vary in length as indicated in Figs. 1 and 3, each one being of a suitable height to coöperate properly with its associated type bar and near its upper end each one of said lever arms is connected by a link 27 with the heel of one of the type bars. Each of the forward arms 17 of the key levers at its forward end projects through a vertical slot in the stem 28 of a printing key 29. The forward end of the lever arm 17 is formed with an open slot 30 in which lies a pin 31 extending through the key stem 28. The keys 29 are arranged in four banks as usual and the lever arms 17 terminate at corresponding points. Each of the key stems is guided near its upper end in a transverse frame bar 32 and at its lower end in a transverse frame bar 33, there being four pairs of these frame bars, one for each tier of keys. The construction is such that when any key 29 is depressed the lever arm 17 is depressed and the upper end of the lever arm 16 is moved toward the front of the machine and actuates the corresponding type bar. In order to lock the type bars against rebound each of them is formed or provided on its under side with a small hook 34, and each of the lever arms 16 is formed at its upper end with a corresponding hook 35 which normally engages the hook 34 as

shown in Fig. 1. In order to allow these two hooks to move into and out of engagement, a slight extent of lost motion is provided between the lever arm 16 and the link 27 as shown in Fig. 2, where it will be seen that the forward end of said link is formed or provided with a pin 36 which projects into a hole 37 in the lever arm and that said hole is slightly elongated in a front and back direction. When the key 29 is operated, the first effect of its depression is to take up the lost motion at the point 36, 37, which moves the hook 35 out of the way of the hook 34 before the type bar begins to move; and when the type bar returns to normal position, the lever arm has a slight additional motion toward the rear which instantly brings the two hooks into engagement. As shown in Fig 3, each of the lever arms 16 near the ends of the segment is bent in radially so as to bring its hook 35 into proper relation with the hook on the type bar. The described devices furnish a very simple and effective means for locking the type bars against rebound.

The plate 23 may be secured in the machine in any suitable manner. As here shown, however, it is secured to the detachable frame comprising the segment 10 and 12 and the bars 13. To this end two posts 38, one at either side of the machine near the front, are secured rigidly to the respective bars 13 and each of said posts is shodered at its bottom and passes through the plate 23 which is secured thereto by a nut 39. A third post 40 is secured to the segment 10 at the middle of the machine and at its bottom has the plate 23 secured to it in the same manner as the posts 38. By this construction the key levers and type bars may all be assembled and connected up outside of the machine and the whole system can be inserted in the machine, the key levers at their forward ends being thrust into the key stems 28.

In order to make the leverage of the several keys on their respective type bars substantially uniform throughout the system, the arms 18 of the key levers are made of different lengths; that is to say, they terminate at different distances from the front of the machine, as clearly shown in Figs. 1 and 5. In the latter figure most of the pivots 20 are indicated only by heavy cross lines. The location of each of these pivots in a front and back direction, is determined by taking account of the length of the forward arm 17, that is to say, which of the four banks of keys that particular lever leads to, and also by taking account of the various lengths of the arm 16 of the key levers. Each pivot 20 is located so as to give that particular lever the proper ratio between the horizontal and upright lever arms. For the keys in any given tier, the

pivots near the middle of the machine are also comparatively near the front of the machine and the pivots near the sides are progressively farther toward the rear; and the pivots for the forward tier or bank of keys are nearer to the front of the machine than those of the other banks. It will be perceived that some of the pivots are at some distance back of the upper ends of the lever arms 16 and those particular arms move, when operated, in a path that extends toward the front of the machine and somewhat downward; but in no case is this downward inclination sufficient to be of any detriment to the type action. The pivots 20 of the key levers, are all at substantially the same level, and the points 31 at which said levers are connected with the key stems, are also at approximately the same level as 20 the pivots, so that there is but little sliding of the pins 31 in the slots 30.

The key levers are returned to normal position by a series of restoring springs 41, each connected at its forward end to one of 25 the arms 16 and at its rear end to a hook 42 formed on the rear edge 43 of a sheet metal plate, which plate is secured to a curved cross bar 44. This cross bar is somewhat higher at the sides of the system and curves 30 downward, having its lowest point at the middle of the system. It will be seen that these springs restore the key levers to normal position and also the type bars, and they restore the type bars effectively because they are connected therewith, not indirectly through a system of sub-levers but more directly through the links 27. Acting as they do on the lever arms 16, these springs also hold the hooks 35 in engagement 40 with the hooks 34.

Provision is made for simultaneously varying the tension on the springs 41. To this end the bar 44 is made adjustable in a front and back direction. Two brackets 45 are secured, one to each of the posts 38, by means of screws or pins 46 and each of said brackets includes a tubular portion or barrel that extends toward the rear of the machine and has a slot 47 cut in one side 45 thereof. A long screw 48 extends lengthwise of the tubular portion of each of the brackets 45 and is journaled at its forward end in said bracket and at its rear end each of said screws is formed with a milled head 55 49. A nut 50, threaded on to said screw 48, fits into the bore of the tubular part of the brackets and has an arm 51 extending through the slot 47. Each of the arms 51 is slotted at its inner end and the end of 60 the bar 44 engages in said slot where it is secured by a pin 52. In Fig. 4 I have shown one of these pins engaging in an open slot 53 in the bar 44. It will be seen that the bar 44 can be adjusted in a front and back 65 direction by turning the milled heads 49.

Said bar 44 being jointed or pivotally connected to the nuts, prevents binding in case one of the nuts is for a moment adjusted ahead of the other. If preferred, however, the nuts 50, arms 51 and bar 44 may be made 70 into one rigid structure.

The universal bar 25 constitutes part of a pivoted frame, which frame also comprises upright arms 54, to the upper ends of which the universal bar is secured. Each of said arms at its lower end is pivoted on a pin 55 projecting from the side of a special hanger 56 secured to the under side of the plate 23. The two arms 54 are also connected by a cross bar 57 which stiffens the 75 universal bar frame.

Each of the vertical arms 54 has projecting from the lower end thereof toward the front of the machine a horizontal arm 58, the forward end of which lies beneath a pin 59 projecting from the side of a lever arm 60, which at its rear end, is pivoted at 61 in the hanger 56. The two lever arms 60 are connected at their forward ends by a space key or bar 62. Each of the lever arms 60 is held up by a restoring spring 63 connected at its ends to pins 63^a projecting respectively from the lever arm and the hanger 56. The construction is such that when the space key 62 is depressed, the pins 90 95 59 depress the arms 58 and operate the universal bar. Said universal bar may be connected with the escapement and ribbon vibrator, or whatever devices it is required to operate, in any suitable manner. As here shown, one or more arms 64 project toward the rear of the machine from the universal bar 25, to which they are rigidly secured. The arm 64 may have a link 65 pivoted thereto and extending to the escapement or 100 ribbon mechanism, or both. In the present instance, I have shown two of these arms 64, one near the middle of the machine for operating the escapement and the other more to one side for operating the ribbon 105 vibrator. 110

It will be perceived that the universal bar and stops are mounted on the same detachable frame that carries the key levers and type bars. It will also be noted that the 115 universal bar and the space key are mounted on the same hangers 56 so that these two parts can be detached and attached simultaneously.

It will of course be understood that the 120 upper ends of all of the key lever arms 16 will preferably move to the same extent when operated, or substantially to the same extent, and therefore the different key levers will turn through different angles. As the 125 universal bar 25 is a straight bar extending across the machine, in order that the same extent of motion may be imparted to said universal bar by all of the key levers, said key levers are arranged to have different ex- 130

tents of lost motion with relation to said universal bar. In Fig. 1 I have shown one of the middle key levers and also one of the end key levers, and it will be observed that the middle key lever has a considerable extent of lost motion before it takes up the universal bar. The end key lever is formed with a lug or projection 66, which extends toward the front of the machine a considerable distance to cause this key lever to impart a suitable extent of motion to the universal bar. The key levers between the middle and the sides of the system are provided with lugs similar to the lug 66 but differing in height.

It will be observed that the key levers are connected with the type bars through the links 27, each of which is pivoted at one end directly to the type bar and at the other end directly to the key lever. This reduces to a minimum the number of joints to be operated at the depression of a key, and leaves only two joints between the type bar and the universal bar, which is important because it enables the universal bar to be moved more exactly in unison with the type bar than is possible where there are a number of joints between them. It is desirable that the escapement be let off at a definite point in the stroke of the type bar and this point can be regulated with much greater nicety where there is not too long a chain of connections between the type bar and universal bar.

35 Some of the features of the type action described herein, are claimed in my prior application, Serial No. 507,919, filed July 16, 1909.

40 Various changes can be made without departing from my invention.

What I claim as new and desire to secure by Letters Patent, is:—

1. In a front-strike typewriting machine, the combination of a series of front strike type bars, a horizontally disposed frame piece beneath said type bars, a series of key levers pivoted to said frame piece, a series of keys having vertically sliding stems, said key levers each having an upwardly extending arm connected with one of said type bars, a rearwardly extending arm pivoted to said frame piece, and a forwardly extending arm connected with one of said key stems, and all of the key lever pivots being at substantially the same level.

2. In a front strike typewriting machine, the combination of a series of front strike type bars, a horizontally disposed frame piece beneath said type bars, a series of key levers pivoted to the under side of said frame piece, a series of keys having vertically sliding stems, said key levers each having an upwardly extending arm connected with one of said type bars, a rearwardly extending arm pivoted to said frame piece, and

a forwardly extending arm connected with one of said key stems, and all of the key lever pivots being at substantially the same level, and said upwardly extending arms coming up in front of said frame piece.

3. In a front strike typewriting machine, the combination of a series of front strike type bars, a series of key levers, and a series of keys having vertically sliding stems, said key levers having upwardly extending arms connected with said type bars and said key levers having also forwardly extending arms connected with said key stems, and the pivots of said key levers being substantially at the same level and approximately at the same level as the points of connection between said key levers and key stems.

4. In a front strike typewriting machine, the combination of a main frame, a series of front strike type bars, a series of bell-crank key levers connected with said type bars, a type bar segment, a type bar rest, and a support to which said key levers are pivoted, said support, type bar rest and type bar segment being all connected so as to constitute parts of one auxiliary frame, and said auxiliary frame being detachably mounted in said main frame.

5. In a front-strike typewriting machine, the combination of a main frame comprising a top plate, a system of front strike type bars, a system of angled key levers and connections for operating said type bars, and an auxiliary frame detachably mounted in said main frame, said auxiliary frame comprising an upper part secured to said top plate and a lower part connected by posts with said upper part and having said key levers mounted thereon, and said upper part including a segmental support to which said type bars are pivoted and a rest for the free ends of said type bars.

6. In a front strike typewriting machine, the combination of a series of front strike type bars each having a hook thereon, a series of links pivoted to the heels of said type bars, and a series of key operated levers to which said links are connected and each lever having a hook for engagement with the hook of the corresponding type bar.

7. In a front strike typewriting machine, the combination of a series of front strike type bars each having a hook thereon, a series of links pivoted to the heels of said type bars and extending therefrom toward the front of the machine, and a series of key operated levers each connected to one of said links and having a hook for engagement with the hook on the corresponding type bar.

8. In a front strike typewriting machine, the combination of a series of front strike type bars each having a hook, a series of links pivoted to the heels of said type bars

80

- and extending therefrom toward the front of the machine, a series of key operated levers having upstanding arms to which said links are connected and said arms having also hooks to engage the hooks on the type bars to prevent rebound, and the upper ends of such of said lever arms as are away from the middle of the system being bent in radially to bring said hooks into suitable engagement.
9. In a front strike typewriting machine, the combination of a series of front strike type bars, and a series of key levers for operating said type bars, said key levers and said type bars having interlocking catches to prevent rebound of the type bars and said catches being independent of the type bar operating mechanism.
10. In a front strike typewriting machine, the combination of a series of front strike type bars, a series of bell crank key levers, and intermediate connections between said levers and said type bars for operating said type bars, said key levers having upstanding arms beneath said type bars and each of said arms having a device to engage the corresponding type bar at a point remote from its pivot to prevent rebound.
11. In a front strike typewriting machine, the combination of a series of front strike type bars each having a hook thereon, a series of links pivoted to the heels of said type bars and extending therefrom toward the front of the machine, and a series of key operated levers each having lost motion connection with one of said links and having a hook for engagement with the hook on the corresponding type bar.
12. In a typewriting machine, the combination of a series of key operated levers, a series of restoring springs for said levers, a bar to which said springs are secured, two nuts, one at each end of said bar and to which said bar is pivoted, and adjusting screws coöperating with said nuts, whereby the tension of said springs can be regulated.
13. In a typewriting machine, the combination of a series of key operated levers, a series of restoring springs for said levers, a bar to which said springs are secured, two nuts, one at each end of said bar and to which said bar is pivoted, adjusting screws coöperating with said nuts, slotted stationary barrels for said screws in which barrels said nuts travel and through the slots in which said nuts extend for connection with said bar, whereby the tension of said springs can be regulated.
14. In a front strike typewriting machine, the combination of a series of front strike type bars, a series of key operated levers having upstanding arms connected with said type bars, a series of restoring springs connected with said upstanding arms, a cross bar to which springs are connected, and two adjustable pieces, one pivotally connected with each end of said cross bar, whereby the tension of said springs can be regulated.
15. In a typewriting machine, the combination of a type bar, operating mechanism therefor comprising a key actuated upright lever arm and a connecting link between said arm and said bar, and interlocking catch devices one on the type bar and the other on the upright lever arm.

Signed at the borough of Manhattan, city of New York, in the county of New York, and State of New York, this 25th day of October, A. D. 1910.

CLIO B. YAW.
